UNITED STATES PATENT OFFICE.

CARRIE BECK SHELDON, OF GRAND MEADOW, MINNESOTA.

DESIGN FOR A STICK-PIN.

SPECIFICATION forming part of Design No. 29,612, dated November 8, 1898.

Application filed June 6, 1896; Serial No. 594,625. Term of patent 7 years.

To all whom it may concern:

Be it known that I, CARRIE BECK SHELDON, a citizen of the United States, residing at Grand Meadow, in the county of Mower and

State of Minnesota, have invented and produced a new and original Design for Stick-Pins, of which the following is a specification, reference being had to the accompanying drawing, in which the figure thereof is a perspective view illustrative of my design.

The leading or material feature of my design consists of a pin having a crook upon its upper end, with a ball or knob at the end of the crook, a chain leading downwardly from

said ball, and two branch chains which are 15 connected at their lower ends, respectively, to the handle-bar and seat of a miniature bicycle.

What is claimed is—

The design for a stick-pin, substantially as 20 shown and described.

In testimony whereof I affix my signature in the presence of two witnesses.

CARRIE BECK SHELDON.
